(57) **CLAIM**

The ornamental design for an in flight entertainment remote control handset, as shown and described.

DESCRIPTION

FIG. 1 is a front perspective view of the in flight entertainment remote control handset showing the design.

FIG. 2 is a front view of the in flight entertainment remote control handset showing the design.

FIG. 3 is a rear view of the in flight entertainment remote control handset showing the design.

FIG. 4 is a right side view of the in flight entertainment remote control handset showing the design.

FIG. 5 is a left side view of the in flight entertainment remote control handset showing the design.

FIG. 6 is a top side view of the in flight entertainment remote control handset showing the design.

FIG. 7 is a bottom side view of the in flight entertainment remote control handset showing the design.

FIG. 8 is a front perspective view of the in flight entertainment remote control handset showing an alternate configuration of the broken line disclosure.

FIG. 9 is a front view of the in flight entertainment remote control handset thereof.

FIG. 10 is a rear view of the in flight entertainment remote control handset thereof.

FIG. 11 is a right side view of the in flight entertainment remote control handset thereof.

FIG. 12 is a left side view of the in flight entertainment remote control handset thereof.

FIG. 13 is a top plan view of the in flight entertainment remote control handset thereof; and,

FIG. 14 is a bottom plan view of the in flight entertainment remote control handset thereof.

The broken lines shown herein are for illustrative purposes only and form no part of the claimed design.
